(57) **CLAIM**

The ornamental design for a card envelope with an opening for a bottle, as shown and described.

DESCRIPTION

FIG. 1 is a top, left, front perspective view of a first embodiment of the card envelope with an opening for a bottle showing my new design;

FIG. 2 is a top, right, rear perspective view thereof;

FIG. 3 is a front view thereof;

FIG. 4 is a rear view thereof;

FIG. 5 is a side view thereof; and,

FIG. 6 is a rear view of the card envelope shown in an open configuration.

The dash-dash broken line showing of portions of the claimed design is included for the purpose of illustrating environmental structure and forms no part of the claimed design.

The dot-dash lines shown in FIG. 1 represent a bottle and form no part of the claimed design.
